UNITED STATES PATENT OFFICE.

THEODORE BUTLER, OF NEW YORK, N. Y., ASSIGNOR TO THE J. L. MOTT
IRON WORKS, OF SAME PLACE.

AUTOMATIC SIPHON FOR CISTERNS.

SPECIFICATION forming part of Letters Patent No. 425,859, dated April 15, 1890.

Application filed January 29, 1890. Serial No. 338,474. (No model.)

To all whom it may concern:

Be it known that I, THEODORE BUTLER, a citizen of the United States, residing at the city, county, and State of New York, have 5 invented a new and Improved Automatic Siphon for Cisterns, of which the following is a specification.

Cisterns have heretofore been made in which water is allowed to run in a gradual 10 stream, and from which the water is discharged periodically by the action of a float and siphon, the object being to flush a water-closet or urinal automatically.

My present improvement relates to the combination, with a peculiar siphon, of a float at one side, in which is an opening, and connected with this float is a secondary or auxiliary float that serves the purpose of turning the float, so that the opening therein is kept above the 20 surface of the rising water in the cistern until the upward movement of the float is arrested, after which and as the water rises it pours in through the said opening, and the float falls and the siphon is brought into action to 25 discharge the water and flush the closet or urinal, and as the cistern becomes nearly emptied the secondary float serves as a weight to turn the main float and empty the water out of the same preparatory to the operations 30 being repeated.

In the drawings, Figure 1 is a vertical cross-section showing my improvements, and Fig. 2 is a plan view of the floats and lever.

A represents a cistern of any well-known 35 construction, and B a stand-pipe above a coupling C and rising within the cistern, and D is a cock upon its upper end, through which a stream of water of any desired size is allowed to flow constantly into the cistern.

40 The siphon is composed of the following parts, viz: an inner tube a, rising to a seat at 1 and at its lower end connected to a coupling-tube b, externally threaded and having a flange 2, and passing through the bottom 45 of the cistern, to which it is held by a nut 3, there being putty or washers between the parts. From the coupling c d a pipe passes to the closet or urinal. There is an outer tube e, having openings at its lower end, 50 through which the water in the cistern passes to rise between the tubes a e. A tubular

cover or cap f is screwed upon the upper end of the tube e, and the same has a reduced portion f', upon which are arms 4, to which the lever l is pivoted at 10. The pipe h is 55 movable vertically, being guided by the stem h', that passes through the cap f', and this pipe h has around it a valve 7, that closes upon the upper end of the standing tube a, and this pipe h has perforations 6 for allowing water to run off or overflow in case of the apparatus being out of order. The upper end of the stem h' is mortised for the end of the lever l. At the outer forked end k of this lever l is the float i, that is received between the pivots 8 at the ends of the fork, and said float i has connected permanently to it an auxiliary float i'. The float i is slotted at 9 on the extreme edge line of its rotation adjacent to the auxiliary float i', to permit 70 water to flow into and fill the float i.

The operation is as follows, presuming that the float is in the position shown in Fig. 1 by dotted lines, with the valve-seat 5 elevated against the cap and the valve 7 raised 75 above the seat 1 at the upper end of the tube a, and water flowing into and gradually filling the cistern by the cock D: As the water rises in the cistern, the floats i i' move upwardly, the float i' moving faster 80 than the float i and turning the float i on the pivots 8, and the lever l swinging on the pivot 10, and the pipe h gradually descending. The float i' turns the float i, so as to keep the slot 9 therein above the surface of the water flowing into the cistern. The floats i i' gradually reach the position shown in full lines, Fig. 1, where the movement is stopped by the valve 7 closing on the seat 1 at the top of the tube a, and at this 90 point the water passes around and over the float i and within the same through the slot 9. The float i fills and sinks rapidly and elevates the pipe h off the seat 7, and starts the siphon by permitting the water to flow over 95 the top of and down the pipe a and away to the closet or urinal to be flushed. As the cistern becomes nearly empty, the auxiliary float i' acts as a weight to turn the float i on its pivots and discharge its contents into the cistern preparatory to the operations being repeated.

The water discharges by the siphon faster than it flows in by the cock D; hence the seal can be readily broken beneath the lower end of the tube e and the siphon stopped previous to repeating the operations heretofore described.

Should the parts become inoperative, the openings 6 in the pipe h provide an overflow for the water, so that the cistern is not filled to overflowing.

I claim as my invention—

1. The combination, with a cistern, and the water-supplying device for the same, and a valve controlling the discharge, of a float with an opening in it, a lever and connections from the float to the valve, pivots upon which the float is permitted to partially revolve, and an auxiliary float connected with the main float to act as a weight in tipping the float to dis-

charge the water therefrom as the cistern is emptied, and as a float to keep the opening into the main float above water as the cistern fills, substantially as specified.

2. The combination, with a cistern, a pipe for admitting water, the tubes a and e, the cap f, and portion f', of the pipe h and stem h', having the valve at their lower end, and overflow-openings at 6, the pivoted lever l, and forked arm k, the connected floats i i', pivoted in the forked arms, and the float i, slotted at 9, for the purposes and substantially as set forth.

Signed by me this 22d day of January, A. D. 1890.

THEODORE BUTLER.
